CLAIM

What is claimed is the ornamental design for a lighting module locking endcap, as shown and described.

DESCRIPTION

FIG. 1 is a perspective view of one embodiment of a lighting module locking endcap in accordance with the present design;

FIG. 2 is a front view of the lighting module locking endcap of FIG. 1;

FIG. 3 is a rear view of the lighting module locking endcap of FIG. 1;

FIG. 4 is a left, side view of the lighting module locking endcap of FIG. 1;

FIG. 5 is a right, side view of the lighting module locking endcap of FIG. 1;

FIG. 6 is a top view of the lighting module locking endcap of FIG. 1;

FIG. 7 is a bottom view of the lighting module locking endcap of FIG. 1; and

FIGS. 8-11 are progressive front views of the lighting module locking endcap of FIG. 1, illustrating a pair of rotatable lighting assemblies (shown in broken lines) attached to the lighting module locking endcap of FIG. 1 on opposed sides thereof and disposed in various positions;

FIG. 12 is a perspective view of another embodiment of a lighting module locking endcap in accordance with the present design;

FIG. 13 is a front view of the lighting module locking endcap of FIG. 12;

FIG. 14 is a rear view of the lighting module locking endcap of FIG. 12;

FIG. 15 is a left, side view of the lighting module locking endcap of FIG. 12;

FIG. 16 is a right, side view of the lighting module locking endcap of FIG. 12;

FIG. 17 is a top view of the lighting module locking endcap of FIG. 12;

FIG. 18 is a bottom view of the lighting module locking endcap of FIG. 12; and,

FIGS. 19-22 are progressive front views of the lighting module locking endcap of FIG. 12, illustrating a pair of rotatable lighting assemblies (shown in broken lines) attached to the lighting module locking endcap of FIG. 12 on opposed sides thereof and disposed in various positions.

The broken lines provided in the drawings form no part of the claimed design.
